O. O. SONJU

SNOWPLOW

Filed March 19, 1923

Inventor

Ole O. Sonju

By

Ole O. Sonju
Attorney

UNITED STATES PATENT OFFICE.

OLE O. SONJU, OF TWO HARBORS, MINNESOTA

SNOWPLOW.

Application filed March 19, 1923. Serial No. 626,024.

To all whom it may concern:

Be it known that I, OLE O. SONJU, a citizen of the United States, residing at Two Harbors, in the county of Lake and State of Minnesota, have invented certain new and useful Improvements in Snowplows, of which the following is a specification, reference being had therein to the accompanying drawing.

10 This invention relates to snow plows and has particular reference to one designed to be attached to a large tractor and used in clearing roads of heavy snow drifts.

In many parts of the country where heavy snow falls are frequent it is found that the snow will drift from one side of the road to the other, that is the snow on one side will be much deeper than on the other, making it almost impossible to do effective work with an ordinary V-type plow, and to design a plow which will clear a road of such heavy drifts in the most effective manner is the principal object of my present invention. In plowing through heavy drifts it is also found that the plow will take the line of least resistance through the snow and be pushed laterally thereby, and another object of my invention is to provide a plow with means to steer it into the drift where and when desired.

Other minor objects and advantages of the invention will appear in the further description thereof:

Referring to the accompanying drawing forming part of this application, in which like reference characters indicate like parts:

Figure 1 is a top plan view of my improved plow;

Figure 2 is a side elevation of the same;

Figure 3 is a front elevation;

Figure 4 is a section on the line 4—4, Fig. 2; and

Figure 5 is a rear elevation of the plow.

1 represents the land side sheet of the plow, the forward end of which inclines rearwardly slightly, to the lowermost forward corner of which is attached in any desirable manner the plow share 2, and the bottom edge of the sheet 1 is bent over at right angles, having the sleigh runner 3 secured thereto in any desired manner.

To the rear of the plow share is fitted the arcuately shaped and rearwardly inclined mould board 4, one end of which is secured by suitable angle iron to the sheet 1, and the other end is braced by a suitable bracing plate 5, which is riveted to the mould board 4, and to the lower end of which is attached the sleigh runner 6. To reinforce the lower end of the mould board I have provided therefor the grader blade 7 which forms a continuation of the plow share and is attached to the mould board in any desired manner.

Intermediate of the sheets 1 and 5 is securely fixed, as by the brackets 8, the heavy channel 9, to which is bolted two pairs of angle clips 10, these angle clips being provided for suitable attachment of the plow to a tractor or other power driving mechanism, in the most convenient manner.

In plowing a road with the plow here described, the sheet 1 will be driven into the deepest part of the snow on the road being cleared, but it is found by experience that unless some means is provided to keep the sheet 1 headed into the drift, the tractor will be helpless to keep the plow on its course. Therefore I have shown the forward end 11 of the sheet 1 as being hinged thereto, the upper end of said hinged connection being provided with a worm wheel 12, which meshes with the worm 13, fixed to the end of the rod 14, supported by the suitable supporting brackets 15, fixed to the sheet 1. The rod 14 extends rearwardly a sufficient distance to be in convenient access of the driver of the tractor, and at the rear of the rod is provided the steering wheel 16.

Just back of the plow share 2, and secured to the sheet 1 and the mould board 2, I have shown the breaker sheet 17, the same being for the purpose of breaking or loosening up the snow and directing it off in the direction of the mould board, thus greatly reducing the resistance of the snow when the plow is being pushed therethrough.

From the foregoing it is evident that I have provided an exceedingly practical snow plow which will effectively remove heavy snow drifts and not be forced from its course by the weight of the snow or the

depth thereof, and it is obvious that various modifications, within the scope of the appended claims, may be resorted to without departing from the spirit of the invention.

5 Having thus described my invention, what I claim and desire to secure by Letters Patent, is:

1. The combination with a snow plow of the character described having a mould board and landside sheet, of steering means

at the forward end of the landside sheet for directing the course of the plow.

2. A snow plow comprising in combination a landside sheet, a mould board, a breaker sheet fitted therebetween, and means for steering the forward end of the landside sheet.

In testimony whereof I hereunto affix my signature.

OLE O. SONJU.
